The ornamental design for a manual roll dispenser with axle, as shown and described.

DESCRIPTION

FIG. 1 is an isometric view of a manual roll dispenser with axle according to my new design.

FIG. 2 is a front view of the manual roll dispenser with axle of FIG. 1.

FIG. 3 is a rear view of the manual roll dispenser with axle of FIG. 1.

FIG. 4 is a top view of the manual roll dispenser with axle of FIG. 1.

FIG. 5 is a bottom view of the manual roll dispenser with axle of FIG. 1.

FIG. 6 is a left side view of the manual roll dispenser with axle of FIG. 1, the right side view being a mirror image.

FIG. 7 is an isometric view of the manual roll dispenser with axle of FIG. 1 illustrating in the dispenser with a full axle in phantom; and,

FIG. 8 is a top view of the manual roll dispenser with axle of FIG. 7 illustrating the full axle in phantom.

The portions of the drawings appearing in broken lines are for environment only and do not form a part of the claimed design.
